UNITED STATES PATENT OFFICE.

JOSEPH S. GALESKI, OF RICHMOND, VIRGINIA.

EYEGLASS-GUARD.

No. 924,226.

Specification of Letters Patent.

Patented June 8, 1909.

Application filed May 19, 1908. Serial No. 433,715.

To all whom it may concern:

Be it known that I, JOSEPH S. GALESKI, citizen of the United States, residing at Richmond, in the county of Henrico and State of Virginia, have invented certain new and useful Improvements in Eyeglass-Guards, of which the following is a specification.

This invention comprehends certain new and useful improvements in eyeglass guards, 10 and relates particularly to improvements in that type of guards which embody a primary bearing surface designed to engage the more bony portion or bridge of the wearer's nose, and a secondary bearing surface or portion, 15 designed to engage the fleshy portion of the nose above the bridge so as to assist in holding the eyeglasses securely in place without any undue pressure and its consequent discomfort.

20 My invention has for its primary object, an improved construction of eyeglass guard of this character which will be efficient in operation and which will possess the characteristics of symmetry of appearance, considerable flexibility and a wide range of adjustability.

With this and other objects in view that will more fully appear as the description proceeds, the invention consists in certain 30 constructions, arrangements and combinations of the parts that I shall hereinafter fully describe, and then point out the novel features thereof in the appended claims.

For a full understanding of the invention 35 and the merits thereof, and to acquire a knowledge of the details of construction, reference is to be had to the following description and accompanying drawing, in which:

Figure 1 is a perspective view of a pair 40 of eyeglasses equipped with one embodiment of my invention; Figs. 2 and 3 are front and rear views respectively of one form of guard showing it detached; Fig. 4 is an end view of one embodiment of the invention; Fig. 5 45 is a face view of such embodiment, and illustrates one of the adjustments that may be effected; Figs. 6 and 7 are front and rear views respectively of a slightly modified form of the invention; Figs. 8 and 9 are end 50 views, on an enlarged scale, of the form illustrated in Figs. 6 and 7, Fig. 9 being designed to illustrate particularly an adjustment of which such form is susceptible; Figs. 10 and 11 are front and rear views 55 respectively of another modification; Figs. 12, 13 and 14 are end views in the nature

of diagrams to illustrate the capability of my invention to adjustment in certain respects hereinafter specifically pointed out; and Figs. 15, 16, 17 and 18 illustrate other 60 modifications.

Corresponding and like parts are referred to in the following description, and indicated in all the views of the drawing, by the same reference characters.

Referring to the drawing, the numeral 1 designates the lenses of a pair of eyeglasses, 2 the bridge or spring, and 3 the stud boxes designed to receive the ends of the spring and the ends of the guards.

In that form of my invention illustrated in Figs. 2, 3, 4 and 5, 4 designates the primary arm of the guard, 5 the secondary arm, and 6 the cross bar which connects said arms together. The primary arm 4 is formed at 75 its upper end with an aperture designed to receive the screw of the stud box, and the said primary arm is comparatively rigid and extends directly downward from the stud box, and is designed to take the proper hold 80 on the bony portion of the nose, while the secondary arm 5 is flexible and thus puts a firm but gentle pressure upon the fleshy portion of the wearer's nose, the secondary arm extending above the bridge or bony portion 85 of the wearer's nose when the guard is properly adjusted and worn. The cross bar 6 is connected preferably permanently to both the primary and secondary arms, so as to form practically an integral structure, and 90 the said cross bar 6 is joined to the primary arm at the front edge thereof, then extends backwardly past the primary arm and is finally joined to the secondary arm at the rear edge of the latter. It is to be particularly noted that the connection between the cross bar 6 and the secondary arm 5 is at 95 the rear edge of said secondary arm.

In that form of the invention illustrated in Figs. 6, 7, 8 and 9, 4^a designates the primary arm or bearing surface, 5^a the secondary arm and 6^a the cross bar. The only difference between this form and that before described, resides in the fact that the cross bar 6^a is curved more than the cross bar 6, 100 and is connected to the rear edge of the primary arm instead of the front edge thereof. It is to be noted, however, that in this form also, the cross bar is connected to the rear edge of the secondary arm. In both 105 of these forms, the cross bar is connected to the middle of the secondary arm, as shown.

Figs. 10 and 11 illustrate substantially the same construction, 4^b designating the primary arm, 5^b the secondary arm and 6^b the cross bar. This form differs from the forms before described in that both of the bearing surfaces are wider and are open or frame-like, as shown; and the cross bar 6^b is angular, first extending rearwardly, when in position, and then slightly in an upward direction. The cross bar, in this form still adheres to the main principle of my invention, in that it is secured to the rear edge of the secondary arm or bearing surface.

By connecting the cross bar to the rear portion of the secondary arm, or bearing surface, the fitter is enabled to adjust the guard in the following advantageous and peculiar ways. In the first place, as best illustrated in Fig. 5, it will be seen that the fitter is enabled to raise or lower the one bearing surface relative to the other and yet maintain the two bearing portions parallel to each other. Furthermore, it will be seen that the cross bar may be curved to a greater extent than that shown, or straightened out for instance from the form illustrated in Fig. 8 to that illustrated in Fig. 9, so as to regulate the distance between the primary and secondary portions according to the requirements of different cases. A still more important result is accomplished by my invention, in that the fitter is enabled to "angle" the secondary portion, so as to accurately fit the shape of the wearer's nose without varying the distance between the secondary portions. This is clearly illustrated in Figs. 12, 13 and 14.

Figs. 15 to 18 illustrate other modifications. In that form shown in Figs. 15 and 40 16, the primary arm 4^c is provided with an offset finger 7 for use by persons having unusually long eye lashes. In that form illustrated in Figs. 17 and 18, the primary arm 4^d is open or framewise at its lower end, 45 while the secondary arm 5^d is provided with the tortoise shell or cork pad as shown, this

form being, in fact, the combination of forms illustrated in Figs. 6 to 10. This last named form as well as the other forms of the invention embody the feature of having the cross 50 bar connected to the rear edge of the secondary arm.

Having thus described the invention, what I claim is:

1. An eyeglass guard comprising a main 55 or, primary arm, arranged for attachment to the stud box, a secondary arm and a cross bar connecting the two, the cross bar being connected to the rear edge of the secondary arm. 60

2. A nose guard of the character described, comprising a main or primary arm, arranged for attachment to the stud box a secondary arm and a cross bar connected to the front edge of the primary arm and to the rear edge 65 of the secondary arm. 65

3. A nose guard of the character described, comprising a main or primary arm, arranged for attachment to the stud box a secondary 70 arm and a curved cross bar connecting the said arms together and attached to the secondary arm at the rear edge thereof. 70

4. A nose guard of the character described, comprising a primary arm arranged for attachment to the stud box, a secondary arm, and a cross bar connected to the primary 75 and also to the secondary arm at the middle and rear edge thereof. 75

5. A nose guard of the character described, comprising a primary arm arranged for attachment to the stud box, a secondary arm, and a cross bar connected to the front edge 80 of the primary arm and extending rearwardly past said arm and connected to the rear edge of the secondary arm and at the 85 middle thereof. 85

In testimony whereof I affix my signature in presence of two witnesses.

JOSEPH S. GALESKI. [L.S.]
